UNITED STATES PATENT OFFICE.

HARRY F. HUSTED, OF SHAVERTOWN, PENNSYLVANIA.

CONDIMENT HOLDER.

Application filed July 30, 1927. Serial No. 209,481.

This invention relates to a condiment holder, more particularly to a combined salt and pepper shaker, but it is to be understood that it may be employed for any purposes for which it is found applicable, and the invention has for its object to provide, in a manner as hereinafter set forth, a device of such class capable of being used for selectively discharging different condiments therefrom, such as salt or pepper when desired.

Further objects of the invention are to provide, in a manner as hereinafter set forth, a condiment holder for the purpose referred to, which is simple in its construction and arrangement, strong, durable, compact, sightly in appearance, thoroughly efficient in its use, conveniently operated and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a side elevation of a condiment holder in accordance with this invention.

Figure 2 is a vertical sectional view thereof.

Figure 3 is a top plan view.

Figure 4 is a top plan view of the cap for the outer container.

Figure 5 is a fragmentary view, upon an enlarged scale, in vertical section of the holder.

Figure 6 is a fragmentary view, in sectional plan, looking towards the inner face of the cap for the outer container.

A condiment holder in accordance with this invention includes an outer container 1 and an inner container 2 and with the latter of less diameter and height than the diameter and height of the outer container 1. Preferably the containers are of cylindrical contour, but it is to be understood that they can be of any desirable shape. The containers can be constructed of any suitable material, preferably highly polished sheet metal. The outer container 1 com-

prises a body portion 3 having an open top and a closed bottom 4. The body portion 3 at the upper part thereof is threaded at 5. The container 1 as illustrated is provided with a body of salt 6.

The container 2 includes an annular body portion 7 of appropriate height and which is open at each end. The upper end of the body portion 7 is formed with an outwardly extending annular flange 8 and the lower part of the body portion 7 is threaded as at 9. Threadedly engaging with the threads 9 of the body portion 7 is a cup-shaped closure member 10 which constitutes the bottom of the container 2. The member 10 is removable to enable the filling of the container 2 with a condiment and the latter is indicated at 11 and consists of a body of pepper.

Detachably engaging with the threaded part 5 of the body portion 3 is a closure cap for the container 1 and which also provides a closure for the upper end of the container 2. The closure cap for the container 1 consists of a circular disc 11 provided with a depending annular flange 12, which constitutes a rim. The flange 12 is threaded as at 13 for engagement with the threaded part 5 of the body portion 3. The disc 11 is formed with a diametrically disposed slot 14 which extends from one side of the axis of the disc and the latter is also formed with a circular row of extensions 15 struck therefrom to provide a circular row of openings 16. The extensions 15 engage under the flange 8 for the purpose of coupling the body portion of the container 2 against the lower face of the disc 11. The disc 11 is furthermore provided in proximity to its edge with a circular row of openings 17.

Between the openings 16 and the slot 14 the disc 11 is also formed with a circular row of openings 18. The rows of openings 16 and 17 provide discharge outlets for the contents of the container 1 and the row of openings 18 provide outlets for discharging the contents of the container 2.

Common to the rows of openings 16, 17 and 18 is a flat, slidably, spring controlled controlling member therefor and said member comprises a circular body portion 19 formed with an extension 20 which terminates in a depending arcuate flange 21. The body portion 19 is provided with a row of openings 21 for registration with the openings 16, with a row of openings 22 for registration with the openings 18 and with a

semi-circular row of openings 23 for registration with certain of the openings of the row 17 and the openings 23 are disposed upon the same arc as the openings 17.

The normal position of the controlling member is as shown in Figure 3 whereby certain of the openings 17 will be exposed and the remaining openings 17 will be in registration with the openings 23 and further with the openings 22 in registration with the openings 16 whereby the condiment from the container 1 can be discharged. The controlling member is normally maintained in the position as stated by a flat controlling spring 24 which is interposed between the flange 21 and the rim 12 and is also secured to the latter and bears against the flange 21 and which acts to maintain the controlling member in its normal position as shown in Figure 3. By shifting the controlling member upon the disc 11, against the action of the spring 24, the openings 22 will be brought into registration with the openings 18 and the openings 17 will be closed and by such arrangement the condiment from the container 2 can be discharged. When discharging the condiment from the container 2, the controlling member is manually held for the desired period to permit of the discharge of the condiment from the container 2 and when pressure is released on the controlling member, the spring 24 acts to shift the controlling member to its normal position as shown in Figure 3.

For the purpose of guiding the controlling member when shifted in either direction, the body portion 19 of said member is formed with a slot 25 through which extends a guiding means 26, which is in the form of a lug and is struck upwardly from the disc 11.

The controlling member is maintained in close contacting engagement with the disc 11, by a holding spring 27 which is arranged within the container 2 and of less length than the height of the latter. Extending through the controlling spring 27 is a headed coupling bar 28 for the controlling member, and said bar at its upper end is formed with a spherical head 29 seating in a tapered opening 30 formed in the controlling member. The bar 28 extends below the spring 27 and the latter has its lower end connected, as at 31 to said bar 28. The spring 27 at its upper end abuts against the lower face of the disc 11. The bar 28 extends down through the slot 14 and the elements as referred to provide for yieldably coupling the controlling member to the disc.

It is thought the many advantages of a condiment holder, in accordance with this invention and for the purpose set forth, can be readily understood, and although the preferred embodiment of the invention is as illustrated and described, yet it is to be

understood that changes in the details of construction can be had which fall within the scope of the invention as claimed.

What I claim is:

1. A condiment holder comprising an inner and an outer open top container, a closure cap detachably connecting with said outer container and common to said containers and provided with outlets therefor, an apertured, spring controlled slidable member seating on said cap for selectively controlling discharge from said containers, said closure formed with a diametrically disposed slot, said member formed with a tapered opening, a coupling bar provided with a head and seated in said tapered opening, said bar extending through said slot into said inner container, a controlling spring anchored at one end to said bar and having its other end abutting against the inner face of said closure, said slot permitting of the shifting of said bar, and a controlling spring for said member secured to said closure cap and bearing against a depending extension on said member. 90

2. A condiment holder comprising an inner and an outer open top container, a closure cap detachably connecting with said outer container and common to said containers and provided with outlets therefor, an apertured, spring controlled slidable member seating on said cap for selectively controlling discharge from said containers, said closure formed with a diametrically disposed slot, said member formed with a tapered opening, a coupling bar provided with a head and seated in said tapered opening, said bar extending through said slot into said inner container, a controlling spring anchored at one end to said bar and having its other end abutting against the inner face of said closure, said slot permitting of the shifting of said bar, and a controlling spring for said member secured to said closure cap and bearing against a depending extension on said member, said inner container having a flange at its top, and said closure provided with spaced, depending extensions overlapping said flange for fixedly connecting said inner container therewith. 110

3. A condiment holder comprising an inner and an outer open top container, a closure cap detachably connecting with said outer container and common to said containers and provided with outlets therefor, an apertured, spring controlled slidable member seating on said cap for selectively controlling discharge from said containers, said closure formed with a diametrically disposed slot, said member formed with a tapered opening, a coupling bar provided with a head and seated in said tapered opening, said bar extending through said slot into said inner container, a controlling spring anchored at one end to said bar and 120

having its other end abutting against the inner face of said closure, said slot permitting of the shifting of said bar, a controlling spring for said member secured to said closure cap and bearing against a depending extension on said member, said inner container having a flange at its top, and said closure provided with spaced, depending ex-

10 tensions overlapping said flange for fixedly connecting said inner container therewith, and a cup-shaped closure member secured to the inner end of the said cup-shaped closure member being removable.

In testimony whereof, I affix my signature hereto,

HARRY F. HUSTED.
